CLAIM

The ornamental design for a bag for packaging, as shown and described.

DESCRIPTION

The patent or application file contains at least one drawing executed in color. Copies of this patent or patent application publication with color drawing(s) will be provided by the Office upon request and payment of the necessary fee.

1. Bag for packaging
- 1.1 : Front Perspective View
- 1.2 : Back Perspective View
- 1.3 : Front
- 1.4 : Back
- 1.5 : Top
- 1.6 : Bottom
- 1.7 : Right Side View
- 1.8 : Left Side View

(Continued)

The dashed lines shown in the reproductions **1.1** and **1.5** represent perforations (tear slits) to open the bag and form part of the claimed design.

1 Claim, 8 Drawing Sheets
(8 of 8 Drawing Sheet(s) Filed in Color)
